ELECTRIC HEATING PLATE

Etienne Challet, Bern, Switzerland, assignor of
one-fourth to the firm Entreprises Electriques
Fribourgeoises, Fribourg, Switzerland, a firm
of Switzerland

Application September 9, 1940, Serial No. 356,063
In Switzerland July 8, 1940

1 Claim. (Cl. 219—37)

This invention due to Mr. Etienne Challet, Bern, Switzerland, relates to an electric heating plate of the type having at least two heating resistances and a heating body composed of at least two distinct body portions.

The object of the invention is to devise a heating plate of this type which differs from those manufactured hitherto in that each one of the heating resistances provided is applied to both the distinct portions of the heating body.

The invention also consists in the further features as hereinafter described and set forth in the dependent claim.

The accompanying drawing illustrates, by way of example, one embodiment of the invention.

Fig. 1 is a top plan view of the heating plate, showing the two distinct body portions thereof;

Fig. 2 is an elevation of the plate, showing the whole construction thereof, and

Fig. 3 shows the connection scheme of the plate.

The electric heating plate as represented in Figs. 1 and 2 comprises a frame 1 carrying a heating body 2. The latter is constructed of an inner circular plate 2_a slidably mounted on the frame so as to be adjustable in vertical direction, and of an outer annular ring 2_b concentric with said inner plate and formed integral with or suitably secured to said frame. To the lower end of the frame are fixed the terminals 4; moreover, said end of the frame forms a suitable cage adapted to house a compression spring 3 which bears against the inner plate 2_a and tends to raise the same relative to the outer ring 2_b so as to adapt the contacting surface of the heating body to the area of contact of the pan or pot placed on said body. All of these features of construction are known in the art and therefore need not be further described herein.

The heating body 2 accommodates two resistances 5 and 6. The resistance 5 is formed to include two branches 5_a and 5_b connected in series and disposed, one within the mass of the outer ring 2_b, and the other within the mass of the inner plate 2_a. Also the resistance 6 comprises two branches 6_a and 6_b placed within the masses of the outer ring 2_b and the inner plate 2_a, re-

spectively. The current intensity of the heating body 2 may be varied by connecting the two resistances 5 and 6 in parallel, or by utilising only one of said resistances or by connecting them 5 in series; the heating effect of the body 2 is thus stepped to three different degrees. It is to be seen, however, that in each of the three cases the whole of the heating body 2 is heated since both the distinct body portions i. e. the inner 10 plate 2_a and the outer ring 2_b are always heated by one of the resistances applied to them, whereas in known heating plates heretofore constructed it is generally found that each of the resistances provided is applied but to a single portion of the heating body. Consequently, when disconnecting one of said resistances the corresponding portion of the heating body is not heated but makes use of the heat transmitted to the pan by another heated body portion, the result of this known 15 arrangement being an unequal distribution of heat as also a loss of heating power.

It should be understood that it is not intended to limit the invention to the exact details of construction shown and described, for various modifications within the scope of the claim may occur to persons skilled in the art. In particular, the invention may be applied also to heating plates having a heating body with fixed outer and inner body portions or a heating body comprising more than two distinct body portions.

30 What is claimed and desired to be secured by Letters Patent is:

In an electric heating plate of the kind having at least two concentric units mounted for relative vertical resilient displacement in a rigid frame, the combination with said movable units of a resistance assembly comprising at least two concentric resistance elements in each heating unit, electrical coupling connections connecting

35 40 each resistance element of one unit with a resistance element of another unit, said connections being adapted for relative movement of said units, and series or parallel connections of said resistance assembly, whereby four degrees of heat may be equally distributed on the whole heating plate.

ETIENNE CHALLETT.
